ART STUDENT'S COLLAPSIBLE WORK BENCH
Joseph De Sena, 36-27 12th St., Long Island City, N.Y.
Filed Aug. 14, 1963, Ser. No. 302,206
10 Claims. (Cl. 297—156)

This invention concerns a collapsible bench and easel for use by artists and art students.

According to the invention there is provided a bench and easel made of a plurality of hinged panels which can be quickly set up for use and folded for convenient transportation and storage. The panels may be made of metal, plastic wood, tempered hardboard or other suitable rigid material. The easel is arranged on the bench in such a manner that it can be extended or retracted and its angular position on the bench can be changed. The bench has five hinged panels providing a seat and elevated end or back rest. The easel includes two large panels and a plurality of narrow connecting panels for adjusting the easel in various positions. If desired, the easel can be removed and the bench can be used alone.

It is therefore one object of the invention to provide a collapsible bench and easel including hinged panels which can be folded to occupy a small space.

It is another object to provide a collapsible bench and easel as described, wherein the easel can be adjusted to various lengths and angular positions on the bench.

A further object is to provide a bench having a back or end rest formed from five hinged panels with braces to hold the panels in fixed positions with respect to each other.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a perspective view of a bench and easel in set-up position.

FIG. 2 is a side view on an enlarged scale of the bench and easel in partially collapsed or folded position.

FIG. 3 is an exploded perspective view of parts of a brace assembly.

FIG. 4 is a side elevational view of the bench and easel in a set-up position, showing the easel in a different position from that of FIG. 1.

FIG. 5 is a fragmentary side elevational view similar to a portion of FIG. 4, showing the easel in still another position.

Referring to the drawings, there is shown an artist's bench and easel assembly 10 including two rectangular end panels 12, 14 which serve as vertical supports or legs for the assembly. The upper end 12' of panel 12 is secured by a hinge or hinges 16 to a rectangular panel 18. The hinges 16 are spaced slightly from the forward end E of panel 18 so that the upper end of panel 12 will underlay and support panel 18 at end E when the assembly is set up. Hinges 16 may be of conventional type with leaves 15 having interfitting eyes joined by a pin 17. The hinges are located at the underside of panel 18 and the inner or rear side of panel 12.

If desired, a single, piano-type hinge may be employed instead of two hinges 16. Two hinges 20 are provided at opposite sides of the assembly 10. Opposite ends of the hinges 20 are secured to lateral edges of panels 12 and 18. Each hinge has a lower arm 21 provided with a finger 22 to overlay upper arm 23 of the hinge so that the hinges when extended serve as reinforcing corner braces for mutually perpendicular panels 12, 18 at the front end of the assembly 10; see FIG. 1.

Panel 18 serves as the front part of a horizontal seat

2

of the bench portion of the assembly 10. Another rectangular panel 24 serves as a rear part of the horizontal seat. Panel 24 is connected to panel 18 by leaf hinges 25 located at upper sides of the panels on the rear end 5 of panel 18 and front end of panel 24, which ends are abutted to each other when the seat is set up.

In order to reinforce the joints provided by hinges 25, two brace assemblies 30 are provided at opposite sides of the seat. Each brace assembly includes a first brace plate 32 as shown best in FIG. 3. This plate has a channel-shaped central portion 33 which is provided with holes 34 to receive screws 31 for attaching the plate to one lateral edge of panel 18 near its rear end. The plate has two coplanar spaced flanges 36 which extend upwardly and downwardly respectively from the outer edges of central portion 33. Another or second brace plate 32a similar to plate 32 with similar channel-shaped central portion 33' and spaced flanges 36' is secured to one lateral edge of panel 24 near its front end. A slideable channel bar or plate 35 with two inwardly turned flanges 38 is movably engaged on plates 32, 32a. Flanges 38 engage behind or inside of flanges 36 above and below the channel-shaped central portions. The bar 35 bridges the joint at the abutted ends of panels 18, 24 and reinforces the joint. Thus a person can sit astride the seat facing the rear end thereof and the panels 18 and 24 will remain in coplanar horizontal position.

The upper end of vertical support rear panel 14 is connected by leaf hinges 40 to the rear end of horizontal seat panel 24. The hinges are located underneath panel 24 at the front side of panel 14; see FIGS. 2, 4 and 5. This arrangement permits panel 14 to fold against the underside of horizontal panel 24. Two hinges 42 serve as rear corner braces for the seat. Opposite ends of arms 43, 44 of the hinges 42 are pivotally attached to lateral edges of panels 14 and 24. Lower arms 43 have fingers 45 which engage on upper edges of arms 44 to prevent downward collapsing of the hinges as viewed in FIG. 1.

Vertical panel 46 is provided as a back or end rest. 40 This rectangular panel is joined to vertical support panel 14 by leaf hinges 48 at the rear sides of the panels. The upper end of panel 14 and lower end of panel 46 are abutted when the bench is set up as shown in FIG. 1. In order to hold the panels 14 and 46 in a vertical coplanar arrangement and to supplement and reinforce the joint at hinges 48, there are provided two brace assemblies 30' which are similar to assembly 30 shown in FIG. 3. Each of brace assemblies 30' includes a brace plate 32' similar to plate 32. Plate 32' is attached to one lateral edge of panel 14 near its upper end. Another plate 32'' like plate 32' is attached to a lateral edge of panel 46 near its lower end. Slidable channel-shaped brace bar 35' engages on the flanges 36 of the plates 32', 32'' and bridges the joint of the abutted edges of the panels 14, 46. This holds the panel 46 erect and coplanar with lower support panel 14.

The assembly 10 is provided with an easel 50 which can be collapsed as shown in FIG. 2 or set up and used in any one of a number of different positions shown in 60 FIGS. 1, 4 and 5, respectively. The easel includes a first narrow panel 52 which is secured by leaf hinge 54 to the rear end of panel 24 at its upper side. Hinge 54 has a narrow leaf 55 secured to panel 24 and a wide leaf 56 secured to one end of panel 52. Panel 52 is secured by a leaf hinge 58 to a second narrow panel 60. Panel 60 is secured by a leaf hinge 62 to a third narrow panel 64. Panel 64 is secured by a leaf hinge 65 to one end of a long rectangular panel 66. A narrow panel 68 is secured by leaf hinge 70 to the other end of panel 66. A long rectangular panel 72 is secured by leaf spring 74 to narrow panel 68.

FIG. 1 shows one arrangement of the easel 50, in which

panels 52 and 60 are horizontal and supported on the top of panel 24. Panel 64 is coplanar with panel 66 and disposed at an angle or obliquely to the horizontal panel 24 to serve as an inclined support for an artist's painting or drawing work. Panel 68 overlays the top of the panel 46 and panel 72 hangs down at the back of panel 46.

In FIG. 4, only the first narrow panel 52 rests horizontally on panel 24. Both narrow panels 60 and 64 are coplanar with long panel 66 which extends beyond the upper end of panel 46. Both panels 68 and 72 hang down at the back of panel 46. Panels 60 and 64 provide a longer support for an artist's work. The two panels 60, 64 provide a more upright or less inclined surface than the panel 64 alone arranged as shown in FIG. 1.

In FIG. 5, all three narrow panels 52, 60 and 64 are supported on horizontal panel 24. Panel 66 is coplanar with panels 68 and 72 and provide a very long, inclined surface for a large painting upon which an artist sitting astride of the bench, may be working. The angle of aligned panels 66, 68 and 72 is more inclined or less upright than the arrangement of easel panels in FIGS. 1 and 4. It will be noted that the facing edges of panels 66, 68 and 72 are in abutment and that panel 72 is supported on the upper end of panel 46.

FIG. 2 shows the simple manner in which the entire assembly can be collapsed to a very compact size. Panels 12 and 18 fold together. Panels 18 and 24 fold together. Panel 14 folds over panel 24. Panel 46 folds over panel 14.

The wide leaf 56 of hinge 54 supports narrow panel 52 in a vertical or end position, while panels 60, 64 and 66 will extend over panel 46. Panels 68 and 72 will fold under panel 66 and will be disposed over panel 46.

To effect the collapsing of the assembly, brace bars 35 will be moved along brace plates 32a to clear plates 32 and brace bars 35' will be moved along brace plates 32" to clear plates 32'. Hinges will be closed toward the joined ends of panels 12, 18 and panels 14, 24.

It is apparent that the easel can be removed from the bench by detaching hinge 54 from panel 24, so that the bench can be used alone. Also the easel can be used alone, separate from the bench.

The bench and easel assembly are easily put together with simple tools. It can be very economically manufactured by relatively unskilled labor. It fulfills a long felt need in that an artist can set up a bench and easel quickly in any place he wishes to work. The bench and easel collapse to small size for convenient transportation and storage.

While I have illustrated and described the preferred embodiment of my invention, it is to be understood that I do not limit myself to the precise construction herein disclosed and that various changes and modifications may be made within the scope of the invention as defined in the appended claims.

Having thus described my invention, what I claim as new, and desire to secure by United States Letters Patent is:

1. A collapsible bench and easel assembly, comprising first and second panels hinged together at adjacent ends to define a horizontal seat, a third panel hinged at one end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; a fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment.

2. A collapsible bench and easel assembly, comprising first and second panels hinged together at adjacent ends to define a horizontal seat, a third panel hinged at one

5

end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; a fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment, the brace means at the joint of the first and second panels and at the joint of the fourth and fifth panels including pairs of stationary brace plates secured to lateral edges of the first, second, fourth and fifth panels, said brace plates having outwardly extended flanges, and a plurality of channel bars each slidably engaged on flanges of a pair of said brace plates when the bench is set up.

3. A collapsible bench and easel assembly, comprising first and second panels hinged together at adjacent ends to define a horizontal seat, a third panel hinged at one end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment, the brace means at the joint of the first and third panels and the joint of the second and fourth panels including pairs of hinges having pivotable arms extending in alignment diagonally between the horizontal first panel and vertical third panel, and between the horizontal second panel and vertical third panel, the brace means at the joint of the first and second panels and at the joint of the fourth and fifth panels including pairs of stationary brace plates secured to lateral edges of the first, second, fourth and fifth panels, said brace plates having outwardly extended flanges, and a plurality of channel bars each slidably engaged on flanges of a pair of said brace plates when the bench is set up.

4. A collapsible bench and easel assembly, comprising a bench including five panels hinged together at ends thereof to define a horizontal seat, two vertical end supports and a vertical end rest extending upwardly from the seat; and an easel comprising a first narrow panel hinged to one of the five panels at one end of said seat, a second narrow panel hinged to the first narrow panel, a third narrow panel hinged to the second narrow panel, and a long panel hinged to the third narrow panel, whereby said long panel and the narrow panels can be arranged on said seat and against said end rest to provide an inclined support of variable length for an artist's work.

5. A collapsible bench and easel assembly, comprising a bench including five panels hinged together at ends thereof to define a horizontal seat, two vertical end supports and a vertical end rest extending upwardly from the seat; and an easel comprising a first narrow panel hinged to one of the five panels at one end of said seat, a second narrow panel hinged to the first narrow panel, a third narrow panel hinged to the second narrow panel, a first long panel hinged to the third narrow panel, a fourth narrow panel hinged to the long panel, and a second long panel hinged to the fourth narrow panel, whereby the long panels and the narrow panels can be arranged on said seat and against said end rest to provide an inclined support of variable length for an artist's work, and whereby the panels of the bench and easel can be

75

folded compactly with the several panels superimposed upon each other.

6. A collapsible bench and easel assembly, comprising first and second panels hinged together at adjacent ends to define a horizontal seat, a third panel hinged at one end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; a fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment, and an easel comprising a first narrow panel hinged to the second panel at the other end thereof, a second narrow panel hinged to the first narrow panel, a third narrow panel hinged to the second narrow panel, and a long panel hinged to the third narrow panel, whereby said long panel and said narrow panels can be arranged on said seat and against said end rest to provide an inclined support of variable length for an artist's work, and whereby the panels of the bench and easel can be folded compactly with the several panels superimposed upon each other.

7. A collapsible bench and easel assembly, comprising first and second panels hinged together at adjacent ends to define a horizontal seat, a third panel hinged at one end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; a fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment, the brace means at the joint of the first and second panels and at the joint of the fourth and fifth panels including pairs of stationary brace plates secured to lateral edges of the first, second, fourth and fifth panels, said brace plates having outwardly extended flanges, and a plurality of channel bars each slidably engaged on flanges of a pair of said brace plates when the bench is set up, and an easel comprising a first narrow panel hinged to the second panel at the other end thereof, a second narrow panel hinged to the first narrow panel, a third narrow panel hinged to the second narrow panel, and a long panel hinged to the third narrow panel, whereby said long panel and said narrow panels can be arranged on said seat and against said end rest to provide an inclined support of variable length for an artist's work.

8. A collapsible bench and easel assembly, comprising first and second panels hinged together at adjacent ends to define a horizontal seat, a third panel hinged at one end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; a fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment, the brace means at the joint of the first and third

panels and the joint of the second and fourth panels including pairs of hinges having pivotable arms extending in alignment diagonally between the horizontal first panel and vertical third panel, and between the horizontal second panel and vertical third panel, the brace means at the joint of the first and second panels and at the joint of the fourth and fifth panels including pairs of stationary brace plates secured to lateral edges of the first, second, fourth and fifth panels, said brace plates having outwardly extended flanges, and a plurality of channel bars each slidably engaged on flanges of a pair of said brace plates when the bench is set up, and an easel comprising a first narrow panel hinged to the second panel at the other end thereof, a second narrow panel hinged to the first narrow panel, a third narrow panel hinged to the second narrow panel, and a long panel hinged to the third narrow panel, whereby said long panel and said narrow panels can be arranged on said seat and against said end rest to provide an inclined support of variable length for an artist's work, and whereby the panels of the bench and easel can be folded compactly with the several panels superimposed upon each other.

9. A collapsible bench and easel assembly, comprising first and second panels hinged together at adjacent ends to define a horizontal seat, a third panel hinged at one end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; a fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment, and an easel comprising a first narrow panel hinged to the second panel at the other end thereof, a second narrow panel hinged to the first narrow panel, a third narrow panel hinged to the second narrow panel, a long panel hinged to the third narrow panel, a fourth narrow panel hinged to the first long panel, and a second long panel hinged to the fourth narrow panel, whereby the long panels and the narrow panels can be arranged on said seat and against said end rest to provide an inclined support of variable length for an artist's work, and whereby the panels of the bench and easel can be folded compactly with the several panels superimposed upon each other.

10. A collapsible bench and easel assembly, comprising first and second panels hinged together at adjacent ends to define a horizontal seat, a third panel hinged at one end to the other end of the first panel to define a vertical support for the seat, a fourth panel hinged at one end thereof to the other end of the second panel to define another vertical support for the seat parallel to the third panel, brace means for reinforcing joints of the first panel to the second panel, the third panel to the first panel, and the fourth panel to the second panel; a fifth panel hinged at one end to the one end of the fourth panel to define a vertical end rest at the other end of the second panel, and other brace means at lateral edges of the fourth and fifth panels bridging abutting joined ends of the fourth and fifth panels to hold the same in coplanar alignment, the brace means at the joint of the first and third panels and the joint of the second and fourth panels including pairs of hinges having pivotable arms extending in alignment diagonally between the horizontal first panel and vertical third panel, and between the horizontal second panel and vertical third panel, the brace means at the joint of the first and second panels and at the joint of the fourth and fifth panels including pairs of stationary brace plates secured to lateral edges of the first, second, fourth and fifth panels, said brace plates

having outwardly extended flanges, and a plurality of channels bars each slidably engaged on flanges of a pair of said brace plates when the bench is set up, and an easel comprising a first narrow panel hinged to the second panel at the other end thereof, a second narrow panel hinged to the first narrow panel, a third narrow panel hinged to the second narrow panel, a first long panel hinged to the third narrow panel, a fourth narrow panel hinged to the first long panel, and a second long panel hinged to the fourth narrow panel, whereby the long panels and the narrow panels can be arranged on said seat and against said end rest to provide an inclined support of variable length for an artist's work, and whereby the panels of the bench and easel can be folded com-

5 pactly with the several panels superimposed upon each other.
